UNITED STATES PATENT OFFICE.

SIGURD J. A. WIEBE, OF EAST ORANGE, NEW JERSEY, ASSIGNOR TO INTERNATIONAL COMBUSTION ENGINEERING CORPORATION, OF NEW YORK, N. Y., A CORPORATION OF DELAWARE.

DUMPING GRATE.

Application filed February 5, 1925. Serial No. 6,957.

My invention relates to furnace grates, and has special reference to dumping grates for the ash pits of automatic stokers.

An object of the invention is to provide a novel and improved grate of this character.

Another object of the invention is to provide a grate having grate bars of novel and improved construction, which may be easily removed and replaced, and when in place are securely held and the danger of ashes or other fine particles sifting down between them is reduced to a minimum.

The several features of the invention, whereby the above-mentioned and other objects may be attained, will be clearly understood from the following description and accompanying drawings, in which:

Figure 1 is a plan view, partly broken away, of a dumping grate embodying the features of the invention in their preferred form;

Fig. 2 is a side elevation of the same;

Fig. 3 is a sectional view taken on the line 3—3 of Fig. 1;

Fig. 4 is a view similar to Fig. 3 but with the grate bars forming component parts of the grate removed;

Figs. 5, 6 and 7 are sectional views taken on the lines 5—5, 6—6 and 7—7, respectively, of Fig. 3;

Fig. 8 is a sectional view taken on the line 8—8 of Fig. 1; and

Fig. 9 is a sectional view taken on the line 9—9 of Fig. 3.

The dumping grate illustrated in the drawings is particularly adapted for use in the ash pits of automatic stokers. As shown the grate is provided with a box-like frame 2 having one end secured on the squared portion of the usual rock shaft 4. The rear or pivoted end of the grate is substantially cylindrical and any suitable and well known means may be provided for directing air through the ends of this cylindrical portion and into the interior of the grate. This rear end of the grate is made in two sections that are secured together by bolts 6 so as to permit the grate to be removed and replaced on the rock shaft 4. The grate frame is

provided with a bottom wall 8, and side walls 10. The parts above described are of a common construction.

In the illustrated construction, the upper edge of each of the side walls is inclined downwardly and forwardly which positions its lower or forward end in proximity to the bottom wall, the extremity of each side wall being arranged substantially vertical and spaced from the extremity of the bottom wall so as to provide a shoulder 12.

The top wall of the grate is made up of a plurality of grate bars which extend transversely of the frame and are arranged in overlapping relation and with their ends mounted upon the top longitudinal edges of the frame. The bars are so constructed and arranged as to permit them to be easily removed and replaced and when in place are securely held. As shown the grate bars consist of a series of three bars 14, and front and rear end bars 16 and 18, respectively.

Each of the bars 14 is provided with a forward portion 20 of the same inclination transversely as that of the top longitudinal edges of the side walls of the frame, and the forward part 22 of the under side of the portion 20 is substantially horizontal, while the remaining portion thereof is arranged substantially in the plane of the top edges of the side walls of the frame. Each bar 14 from its forward edge to a point spaced a distance back of said horizontal side portion 22 overlaps the rear portion of the bar immediately in front, the lowermost bar 14 of the series overlapping the front end bar 16.

The overlapping portion of each bar is provided with a series of spacing ribs 24 extending transversely of the bar and forming air passages of uniform depth throughout leading from the interior of the grate. Each bar 14 is also provided with a horizontal portion 26 extending from the inclined portion 20 to a line that is directly beneath the line that defines the rear edge of the horizontal underside part 22 of the inclined portion 20, and from that point the bar is inclined upwardly and rearwardly parallel with the adjacent portion of the bar immediately at the rear, the three bars 14 being

of the same construction and interchangeable, and the rear portion of the uppermost bar 14 underlying the forward portion of the rear end bar 18. The rear portion of each bar 14 that extends beneath the plane of the top edges of the side walls, has its ends received in suitably shaped recesses 28 in the side walls of the grate frame. Each of the bars 14 is also provided with a depending rib 30 extending longitudinally thereof and having its ends received in correspondingly shaped recesses 32 in the side walls of the grate frame. The several recesses 28 are continuations of each other and the recesses 32 are continuations of the recesses 28. The top face of each bar 14 is provided with a series of fuel spacing ribs 34 which extend over the forward edge of the bar, over the inclined portion 20, and a distance over the forward part of the horizontal portion 26. Each of the bars is supported by projecting ends 36 thereof which are mounted on the top edges of the side walls of the frame. The forward portion 38 of each end 36 overlaps the rear portion of the end of the bar directly beneath, the adjacent surface portions of adjacent ends being arranged substantially horizontal. The projecting ends 36 of each bar 14 project a distance forwardly of the forward edge of the remaining portion of the bar. It will be understood that the lowermost bar 14 of the series overlaps the lower or front end bar 16 in the same manner that the bars 14 overlap each other. Each bar 14 is provided with a depending reinforcing rib 37 which is arranged parallel with the holding rib 30 and is connected therewith by a series of ribs or webs 39.

40 The front end bar 16 has a substantially horizontal portion 40 which is similar to the horizontal portion 26 of the bars 14, an upwardly and rearwardly inclined rear portion 42 which is similar to the similarly inclined rear portion of the bars 14, and with a longitudinally extending rib 44 which is similar to the ribs 30. The ends of the portion of the bar 16 arranged beneath and between the side walls of the grate frame are received in recesses 46 which are similar to the recesses 28, and the ends of the rib 44 are received in correspondingly shaped recesses 48 which are continuations of the recesses 46. The ends of the bar 16 which are mounted on the top edges of the side walls of the frame correspond to the ends 36 of the bars 14 except that the forward edge of the bar 16 is provided with a depending portion 50 which extends throughout the length of the bar and down over the vertical shoulders 12, and has its lower end surface spaced a slight distance from a flattened portion 52 at the forward end of the bottom wall of the frame, the depending portion 50 being provided with a series of spacing ribs 54 on its underside.

The fuel supporting surface of the grate bar 16 is provided with fuel spacing ribs 56.

70 The rear end bar 18 is provided with an inclined forward portion 58 which is similar to the inclined forward portions 20 of the bars 14; with a depending rib 60 which is similar to the depending ribs 30 and has its ends received in recesses 61 in the side walls of the frame; with projecting ends 62 that are mounted on the side walls and overlap the rear portions of the projecting ends 36 of the uppermost bar 14; and with fuel spacing ribs 64 extending over said inclined forward portion 58 thereof. The rear portion of the bar 18 is set in a suitably formed recess 66 80 in the upper section of the rear portion of the frame, and the bar is securely held in place by means of a bolt 68 which extends through suitable apertures in the bar and in the rear portion of the frame, the bolt hole in 85 the bar being countersunk.

90 The spaces between the end portions of the several bars and the walls of the recesses in which they are received, as above described, are filled with asbestos or other suitable material 70 (Figs. 6 and 7) so as to prevent the ashes and other fine particles from sifting through these spaces and into the interior of the grate.

95 In assembling the several bars on the grate, the lowermost or front end bar 16 is first placed in position and then the remaining bars are applied one after the other, the securing of the upper or rear end bar 18 by means of the bolt 68, effectively cooperating 100 with the holding ribs 30 of the bars 14 and the rib 44 of the lowermost or front end bar 16 to hold all of the bars in place.

105 From the foregoing it will be apparent that a dumping grate is provided in which the top wall is made up of a plurality of overlapping grate bars, the bars other than the endmost ones being of the same construction and interchangeable. Also that the relatively long air passages between the bars 110 which have their rear portions inclined upwardly, effectively prevent any siftings from blocking the passages or entering the interior of the grate through these passages, and as the spaces between the end portions of the 115 bars and the walls of their recesses are compactly filled by the asbestos material 70, it will be apparent that the bars are practically non-sifting. It will also be apparent that the upper bar always prevents the bar 120 immediately below it from lifting up and when the grate is operated and hangs vertically, the holding ribs on the under sides of the bar resting in their recesses in the side walls of the frame prevent each bar from 125 dropping out of its position. Also, the bars are so constructed that they can be put on a frame of any inclination without in any way impairing their efficiency.

130 As will be evident to those skilled in the

art, my invention permits various modifications without departing from the spirit thereof or the scope of the appended claims.

What I claim is:

vide air passages between them, the rear portion of the walls of the space between the overlapping portions of adjacent bars being inclined upwardly and rearwardly with relation to their forward portions, and the major portions of the refuse supporting surfaces of the bars being substantially in the same plane.

8. A dump grate of the class described 10 having, in combination, a boxlike frame pivotally mounted at its rear end, having longitudinal side walls vertically arranged with their upper longitudinal edges inclined downwardly and forwardly, and having a 15 bottom wall, a grate bar extending over the front end of the frame and mounted at its ends on the top longitudinal edges of said side walls, a bar extending over the rear end of the frame and mounted at its ends on the 20 rear portions of the top of the longitudinal edges of said side walls, means comprising a bolt for holding the last-mentioned bar in place, and a series of bars for covering the space between said front and rear bars, each 25 of the bars of said series having its ends mounted on the top longitudinal edges of said side walls and having depending portions adjacent its ends, said side walls having recessed portions for receiving the depending portions adjacent corresponding ends, respectively, of the bars of said series, the forward portion of the lowermost bar of 30 said series overlapping the rear portion of

said front end bar, the rear portion of the uppermost bar of said series underlying said 35 rear end bar, and the forward portion of each bar of said series overlapping the rear portion of the next succeeding bar, the overlapping portions of adjacent bars being spaced apart to provide air passages between 40 them, and the major portions of the refuse supporting surfaces of the bars being substantially in the same plane.

9. A dump grate of the class described 45 having, in combination, a frame pivotally mounted at its rear end and having longitudinal side walls vertically arranged, and a plurality of grate bars mounted on the side walls, each bar having the ends of its forward portion overlapping the tops of said 50 side walls and the surface of said forward portion arranged substantially parallel with the upper edge of the side walls, and its rear portion extending between said side walls and arranged beneath the forward portion 55 of the next succeeding bar, the overlapping portions of said bars being spaced a distance apart to provide air passages between them, and each air passage having its rear portion inclined upwardly and rearwardly 60 with relation to the front portion thereof.

In testimony whereof, I have signed my name to this specification this 2nd day of February, 1925.

SIGURD J. A. WIEBE.
